HERBERT R. SIMONDS, OF DAYTON, OHIO, ASSIGNOR TO THE A. A. SIMONDS & SON COMPANY, OF DAYTON, OHIO, A CORPORATION OF OHIO.

KNIFE-BAR FOR BEATING-ENGINES.

1,093,490.

Specification of Letters Patent. Patented Apr. 14, 1914.

Application filed February 21, 1913. Serial No. 749,916.

To all whom it may concern:

Be it known that I, HERBERT R. SIMONDS, citizen of the United States, residing at Dayton, in the county of Montgomery and 5 State of Ohio, have invented certain new and useful Improvements in Knife-Bars for Beating-Engines; and I do hereby declare the following to be a full, clear, and exact 10 description of the invention, such as will enable others skilled in the art to which it appertains to make and use the same.

My invention consists in the novel features hereinafter described, reference being had to the accompanying drawings which 15 show one embodiment of my invention selected by me for purposes of illustration, together with a slight modification thereof, and the said invention is fully disclosed in the following description and claims.

20 Referring to the accompanying drawings:—Figure 1 represents so much of a beating engine or macerating device for paper pulp as is necessary to be shown in order that a complete understanding of my 25 invention may be had, the said figure showing a portion of the tank with one side removed and the cylinder being provided with the improved knife bar hereinafter more fully described. Fig. 2 represents a section 30 on line 2—2 of Fig. 1. Fig. 2^a is a detailed sectional view of a portion of the mechanism. Fig. 3 is a perspective view of a portion of my improved knife bar illustrating one end of the same and showing in 35 dotted lines the relation of the spacing blocks and retaining ring thereto. Fig. 4 is a transverse sectional view of my improved knife bar, portions of the spacing blocks, and the location of the retaining 40 ring being indicated in dotted lines. Fig. 5 represents a top plan view of a portion of the corrugated edge of one of my improved knife bars. Fig. 6 is an edge view of a portion of the knife bar looking at the corrugated portion thereof. Fig. 7 is an end view of a knife bar embodying a slight 45 modification of my invention.

The object of my invention is to provide an improved knife bar for use in the rotated 50 cylinder of a beating engine or pulp macerating device for the preparation of paper pulp which can be inserted in and used in the cylinder of the ordinary commercial machines now in use; which is provided with a 55 transversely corrugated edge portion of

novel construction and which is particularly designed to produce in conjunction with the stationary knives of the machine a wiping or sweeping action produced by holding the knife bars in the cylinder so that they extend rearward of a radial position therein, and also providing means for insuring that the material, which has a tendency to collect between adjacent blades of the cylinder, shall be continually thrown outward by the 60 blades so that all portions of the pulp may be acted upon in the most uniform manner.

In Figs. 1 and 2 I have shown a portion of a beating engine or macerator in order that my invention may be more clearly understood. In said figure, 1 represents a tank for holding the pulp, the forward side of which has been removed to disclose the interior, and 2 represents the usual central partition of the tank around which the material circulates. 3 represents the stationary knives, or bed and 4 represents the beating cylinder which is of usual construction and comprises a plurality of disks, 5, mounted on a shaft, 6, supported in vertically adjusted bearings, 7, of any desired construction above the bed, 3. The cylinder disks, 5, are provided with a plurality of knife bar receiving recesses, one of which is illustrated in Fig. 2^a, each having one wall, 5^a 85 substantially radial or parallel to a radius and the opposite wall, 5^b, inclined with respect thereto and diverging therefrom outwardly from the bottom of the recess. In accordance with my invention the drum is 90 so located that when rotated in the direction of the arrow, Fig. 1, the radial side of the recess will be on the forward side of the blade, having reference to the direction of rotation. For convenience of reference 95 herein, I will designate the substantially radial wall of the recess as the straight wall, and the opposite wall as the inclined wall which will be readily understood with reference especially to Fig. 2^a and referring 100 to the knife bar hereof I will designate the leading face having reference to the direction of rotation as the forward face of the bar and the opposite face as the rear face of the bar. The several knife bars after 105 being placed in engagement with the recesses of the disks, 5, are held in place therein by a ring, 8, (see Fig. 1) which engages recesses in the ends of the knife bars and clamps them firmly to the outermost disks, 110

said rings being ordinarily shrunk on to said disks and bars and the bars are further held in place by wooden wedge blocks, 9, which are driven between them as illustrated in Fig. 1.

- 5 My preferred form of knife bar is illustrated in detail in Figs. 3, 4, 5 and 6 which show an embodiment of my invention selected by me for purposes of illustration.
- 10 The knife bar, 10, comprises in an integral structure two portions which for convenience I designate as the stock portion, 11, and the edge or blade portion, 12, the stock portion being that portion which engages
- 15 the recesses in the cylinder and lies between the spacing blocks or wedges thereof, and the edge portion being the portion which projects beyond the wedge blocks. The stock portion of the bar has two plane faces,
- 20 11^a and 11^b, the face 11^a being disposed perpendicularly to the inner edge, 11^c and the outer edge 12^c and the face 11^b being disposed angularly to the face 11^a and diverging therefrom outwardly from the inner
- 25 edge 11^c and being so shaped as to fit the recesses in the cylinders now in ordinary use in this class of machines. The stock portion of the bar is provided at each end with a recess or notch, 11^d, leaving a tongue, 11^e, between said recess and the inner edge 11^c which is of slightly greater depth than the recess, so that the retaining rings when shrunk in position will have a firm engagement with said tongue and firmly hold the
- 30 bars in place. The edge portion, 12, of the bar is provided with corrugations extending transversely of the length of the bar, the alternating corrugations having their axes disposed angularly to each other, as indicated by the dotted lines, *x*—*x* and *y*—*y* in Fig. 4, and diverging from each other outwardly from the stock portion. In the preferred form of my improved knife bar those corrugations which present their convex
- 35 faces to the forward side of the bar, the direction of rotation being indicated by the arrow, *z*, in Figs. 3 and 4, have the apices of said convex faces in substantial alinement with the face, 11^b, of the stock portion. The
- 40 alternate corrugations which present their concave faces, 12^a to the forward side of the bar have said faces disposed angularly to the plane of the rear face, 11^a of the stock portion, the said concave faces being
- 45 given a "rake" outwardly and rearwardly for two important purposes, one of which is to produce a wiping action on the pulp as the knife bars pass over the stationary bed, 3, as is clearly shown in Fig. 1, and the
- 50 other is to cause the said concave faces to so act upon the material during the revolutions of the cylinder as to throw outwardly the material between adjacent blades of the cylinder and prevent it from traveling
- 55 around and around with the cylinder. The

corrugated edge portion, 12, of the blade is made much thinner than the stock portion and is given a substantially uniform thickness for a distance back from its outer edge in order that the outer edge of the face, 12^c, may be ground when necessary without increasing the width of said face. The said corrugated portions are, however, gradually made thicker adjacent to their line of union with the stock portion, thereby forming curved or inclined shoulders, 12^d and 12^e which terminate at the line of union with the stock portion indicated by the dotted line, 10^a, in Fig. 3 at which point the bar has its greatest thickness. It will thus be seen that the shoulders, 12^d and 12^e, in conjunction with the thick end of the stock into which they merge form braces which greatly strengthen and reinforce the corrugated edge portion of the bar to resist the strain to which it is subjected and which is exerted upon the edge portion substantially perpendicularly thereto, and this construction in conjunction with the corrugations of the edge portion give the blade great stiffness and strength with a minimum of weight and material. The shoulders, 12^d on the forward side of the blade which form continuations of the concave faces 12^a also serve another important function in that they act as cams or inclined faces which assist in throwing the material between the adjacent blades of the cylinder outward. It will also be noted that the convex portions of the corrugations, on the forward side of the bar or blade, have a tendency to crowd the material in opposite directions longitudinally of the blade and into contact with the shoulders, 12^d, and concave faces, 12^a, and contribute to this important result.

I have stated heretofore that the forward concave faces, 12^a, of the edge portion are given a rake outwardly and rearwardly, and, as a matter of fact, I prefer to impart this rake to the entire alternating corrugations which present their concave faces to the forward side of the bar by bending said corrugations inward at their inner ends and forming a slight shoulder, 12^f, on the rear face of said corrugations as is clearly shown in Fig. 4, and this is my preferred construction. The rear edge of the outer face, 12^c, at the rear of said alternating corrugations, will preferably, however, be in alinement with the rear face, 11^a, of the stock portion of the bar.

In placing my improved bar in the recesses of the cylinder I prefer to place it with the front face, 11^b, of the stock portion, which is the inclined face of the stock portion, in engagement with the straight face of the recess, the straight face, 11^a, of the bar being in contact with the inclined face 5^b, of the recess, as this imparts a rearward rake to the entire bar and tends to give it

the sweeping or wiping action before described as well as forcing the material outwardly from the cylinder, and this effect is increased by imparting the rake before described to the alternate corrugations presenting their concave faces to the front of the bar, and the shoulders, 12^a, further assist in forcing the material outwardly. By thus setting the bars in the cylinder so as to rake backward the advanced portions of the outermost edge, 12^c, extend outwardly from the cylinder a greater distance than the rear-most portions of said edge. Hence in looking down upon the corrugated edge as in Fig. 5, the outer extremity thereof appears to be slightly curved and as the edge passes over the straight faces of the knives of the bed 3, opportunities are provided for the material to continually redistribute itself as it is acted upon, and thus a more uniform treatment of the pulp is effected.

In Fig. 7, I have shown a slight modification of my improved knife bar which is substantially identical with the form shown in Figs. 3 to 6 inclusive except that the alternate corrugations presenting their concave faces to the forward side of the edge or blade portions are not given the backward rake which I have previously described, but, on the contrary, the said alternate corrugations have their axes parallel to the plane of the rear face, 21^a, of the blade, the corrugations presenting their convex faces to the forward side having their axes parallel to the face 21^b, of the stock portion of the bar, and said corrugations being thickened adjacent to their line of union with the stock portion to form the forwardly and rearwardly disposed inclined faces 22^a and 22^b, the stock portion of the bar being indicated generally as 21 and the edge or blade portion being indicated generally as 22. Of this form of bar the rear face 21^a is disposed substantially perpendicularly to the inner edge 21^c and the outer edge 22^c, and forms the straight side while the face 21^b of the stock portion diverges from the face 21^a and engages the straight face 5^a of the recess in the cylinder. Thus the bar when placed in the cylinder will have a general backward rake as before described with reference to the preferred form of blade, thus imparting the sweeping or wiping action on the material and tending to discharge the same outwardly from between the bars, which latter action will be facilitated by the forwardly disposed shoulders, 22^a. The shoulders 22^a and 22^b also reinforce the edge or blade portion and transmit the strain on the outer edge of the bar to the thickest portion of the bar and this modified form of knife bar is capable of advantageous use, although I prefer the construction illustrated in Figs. 3 to 6. In the tank 1 in conjunction with the bed, 3, are usually provided an inclined

surface, 25, on one side of the cylinder and a concave surface, 26, on the other side partially surrounding the cylinder for the purpose of deflecting the material to the cylinder and bed and insuring the 70 propulsion of the material in the tank so as to bring fresh portions of the material continuously between the cylinder and bed. By reference to Fig. 1 it will be observed that in the rotation of the cylinder the corrugated knife bars approach the bed, 3, with a wiping or sweeping action which disintegrates the fibrous material without cutting or shearing the fibers thereof, and it will also be seen that the material which necessarily is collected between the adjacent blades of the cylinder will be discharged therefrom over the top edge of the concave portion 26, the material then passing around the center partition, 2, and being 80 continuously treated until the proper degree of maceration has been attained.

What I claim and desire to secure by Letters Patent is:—

1. A knife bar for beating engines comprising a stock portion to engage the beating cylinder and an edge portion of reduced thickness extending along the outer portions of the bar, and corrugated transversely of the length of the bar, the alternate corrugations having their axes inclined to each other, said axes diverging toward the outer edge of the bar. 90

2. A knife bar for beating engines comprising a stock portion to engage the beating cylinder and a reduced edge portion corrugated transversely of the length of said bar, the alternate corrugations having their axes disposed angularly to each other and diverging toward the outer edge of the 100 knife bar, said corrugations increasing in thickness at their junction with the stock portion, forming inclined shoulders for reinforcing the edge portion of the bar and assisting in discharging material from between adjacent bars of a cylinder. 105

3. A knife bar for beating engines comprising a stock portion to engage the beating cylinder having its front and rear faces disposed angularly to each other and diverging from the inner edge of the bar outwardly, and a reduced edge portion corrugated transversely of the length of the bar, the alternate corrugations having their axes disposed angularly to each other and diverging outwardly from the stock portion, said corrugated portions being gradually increased in thickness adjacent to their union with the stock portion to form inclined shoulders for assisting in discharging material from between adjacent bars of a cylinder said bar having its greatest thickness at the union of said shouldered portions with the stock portion. 115

4. A knife bar for beating engines com- 130

prising a stock portion to engage the beating cylinder having its front and rear faces disposed angularly to each other and diverging from the inner edge of the bar outwardly, and a reduced edge portion corrugated transversely of the length of the bar, the alternate corrugations having their axes disposed angularly to each other and diverging outwardly from the stock portion, 5 said corrugated portions being gradually increased in the thickness adjacent to their union with the stock portion to form inclined shoulders, said bar having its greatest thickness at the union of said shoulder portions with the stock portion, said corrugated portions having the apices of their alternate corrugations at the outer edge of the bar, substantially in the planes of the front and rear faces respectively of 10 the stock portion of the bar.

5. A knife bar for beating engines comprising a stock portion to engage the beating cylinder and an edge portion of reduced thickness, said edge portion being corrugated transversely of the length of the bar, the alternate corrugations having their axes disposed angularly to each other and diverging from their union with the stock portion outwardly, the corrugations presenting their concave faces toward the forward face of the bar having their forward faces inclined outwardly and rearwardly with respect to the plane of the rear face of 25 the stock portion to assist in throwing the material outwardly and imparting a wiping action to the material in connection with the stationary knives of the machine.

6. A knife bar for beating engines comprising a stock portion to engage the beating cylinder and an edge portion of reduced thickness, said edge portion being corrugated transversely of the length of the bar, the alternate corrugations having their axes disposed angularly to each other and diverging 40 from their union with the stock portion outwardly, the corrugations presenting their concave faces toward the forward face of the bar having the portions nearest the stock portion set in from the plane of the rear face of the stock portion, and their axes inclined outwardly and rearwardly therefrom with respect to the plane of the rear face of the stock portion to impart a wiping action to the material and to assist in throwing the material outwardly.

7. In a beating engine, the combination with the cylinder provided with knife receiving recesses, of a knife bar having a stock portion to engage said recesses, and an

edge portion of reduced thickness extending 60 along the outer portions of the bar, and corrugated transversely of the length of the bar, the alternate corrugations having their outer faces inclined to each other and diverging toward the outer edge of the bar. 65 said stock and recesses being constructed to hold the knife bar in such position that the forward faces of the concave portions of the knife bar will extend rearwardly of a radial position, to facilitate the discharge of 70 material from between adjacent knife bars.

8. In a beating engine, the combination with the cylinder provided with knife receiving recesses, of a knife bar having a stock portion to engage said recesses and an 75 edge portion of reduced thickness extending along the outer portions of the bar, and corrugated transversely of the length of the bar, the alternate corrugations having their outer faces inclined to each other and diverging 80 toward the outer edge of the bar, said stock and recesses being constructed to hold the knife bar in such position that the axes of the convex portions on the forward face of the bar will not extend forward of 85 a radial position, and the axes of the concave portions will extend rearwardly of a radial position, to facilitate the discharge of material from between adjacent bars of 90 the cylinder.

9. In a beating engine the combination with the cylinder provided with knife receiving recesses, each having one face disposed substantially radially and the opposed face inclined thereto and diverging therefrom outwardly from the bottom of the recess, of a knife bar having a stock portion provided with a longitudinal face disposed substantially perpendicularly to the edge faces of the knife bar and the opposite face 100 inclined thereto and diverging therefrom outwardly from the inner edge of the bar, said bar having an edge portion of reduced thickness corrugated transversely of the length of the bar, the alternate corrugations 105 having their axes disposed angularly to each other and diverging outwardly from the stock portion, said bar having the perpendicular face against the inclined face of the engaged recess, and means for securing said 110 bar in said recess.

In testimony whereof I affix my signature in the presence of two witnesses.
